UNITED STATES PATENT OFFICE.

WALTER A. KRENTLER, OF DETROIT, MICHIGAN, ASSIGNOR TO KRENTLER-ARNOLD
HINGE LAST COMPANY, OF DETROIT, MICHIGAN, A CORPORATION OF MICHIGAN.

LAST.

Application filed October 3, 1918. Serial No. 256,732.

To all whom it may concern:

Be it known that I, WALTER A. KRENTLER, a citizen of the United States, and resident of Detroit, Michigan (whose post-office address is 1001 Majestic Building, Detroit, Michigan), have invented an Improvement in Lasts, of which the following description, in connection with the accompanying drawings, is a specification, like letters on the drawings representing like parts.

This invention relates to lasts and is particularly concerned with standard heelparts for lasts. As is well understood by those skilled in this art, the changes in the styles of lasts involve chiefly variations in the shape, dimensions and contour of the toe portion of the lasts and rarely involve substantial changes in the heel part of the last. At the same time the heel part is the more expensive portion of the last since it carries all the hardware and requires the greater part of the manufacturing expense both for labor and materials; and this portion of the last, as just stated, does not vary substantially with changes in the style of last. It was therefore proposed many years ago to manufacture lasts having a standard heel part with which any one of a number of foreparts could be used interchangeably so that the change from one style of last to another would involve merely the substitution of a forepart of the new style for the forepart of the discarded style, the same heelpart being used with both foreparts. This construction would have not only the advantage of saving the expense of manufacture of a new heel part, but also that of permitting the use of smaller blocks of wood from which to manufacture the lasts, since obviously a much smaller block is required from which to turn simply a forepart than is necessary to make a whole last.

While a great deal of inventive and development work has been done to accomplish this object and such efforts have extended over a long period of years, none of these efforts have proved commercially successful. There are many reasons for the failure of these efforts, among which may be

mentioned particularly the fact that the standard heel-parts proposed have, in order to possess the degree of indestructibility necessary to produce the advantages sought, been made of metal and were so heavy that they substantially increased the difficulty of manipulating the shoe in presenting it to the various machines and carrying it through the different steps of the process of manufacture. This was objectionable both to the workmen, because it made their labor more arduous, and also to the manufacturers, because the increased weight which the operatives were required to handle reduced production to a very appreciable extent.

A further difficulty encountered with these constructions was that of changing the foreparts; that is, no entirely satisfactory connecting means between the heelpart and forepart has been developed, so far as I am aware, which will permit the degree of interchangeability between the heel and foreparts that is necessary to secure the ends in view and still form an entirely satisfactory union or bond between these parts.

It has also been found that in order to secure the maximum advantage to be gained from the use of a standard heelpart and thus warrant the expense necessary to make this part of the last as indestructible as it should be to properly fulfill its functions, it was necessary to make some provision for adjusting the width of the heelpart so that it could be fitted to foreparts of different sizes or foreparts varying so substantially in style that they involved variations in the width of the rearward end of the forepart that abuts against the heelpart. It is obvious that the capacity for adjusting the dimensions of the heelpart is an especially desirable feature, since it reduces very substantially the number of heelparts that a manufacturer must keep on hand in order to give him an adequate supply of lasts varying substantially in style and size. Attempts also have been made to accomplish this object but these attempts likewise have proved unsuccessful, so far as I have been able to learn, due to the difficulty in making the

heelpart sufficiently rigid while still securing the degree of adjustability necessary or to the difficulty in maintaining smooth, substantially unbroken, shoe supporting surfaces on the heelpart and thus avoid the formation of creases or ridges in the inner surface of the shoe.

The present invention aims to overcome the difficulties which have heretofore existed in the various prior constructions of lasts of the standard heelpart type and to devise a thoroughly practical construction of this character.

To this end the invention provides a heelpart, preferably made of metal, but so constructed that it does not weigh substantially more than a wooden heelpart and still gives the desired rigidity and resistance to breakage which is required to withstand the strains to which it is subjected in use, such for instance as the blows of the heelng machine. The invention also provides a thoroughly practical means for securing the heel and foreparts together which facilitates the interchanging of foreparts and still gives the strength and rigidity necessary between these two parts.

A further feature of the invention is a novel construction whereby the heelpart of the last may be adjusted in width to fit the forepart. Means is provided which not only permit this adjustment, but maintain at all widths substantially smooth, unbroken, shoe supporting surfaces on the heelpart and in which the heelpart is, to all intents and purposes when once adjusted, a rigid one-piece member.

An illustrative embodiment of the invention will now be described in detail and the novel features will be pointed out more particularly in the appended claims.

Referring to the accompanying drawings:

Figure 1 is a side elevation, partly in cross section, of a last equipped with a heelpart embodying this invention, one side of this heelpart being removed;

Fig. 2 is an elevation of the inside of one of the side members of the heel;

Fig. 3 is a bottom view of the heelpart of the last;

Fig. 4 is a front elevation of the heelpart shown in Fig. 3;

Fig. 5 is a bottom view of the heelpart adjusted to a greater width than in the condition shown in Fig. 3;

Fig. 6 is a front elevation of the heelpart shown in Fig. 5;

Fig. 7 is a side elevation of a different form of central or spacing member to be used with the side members of the heelpart shown in the other figures;

Fig. 8 is a side elevation of a still further modified form of central or spacing member;

Fig. 9 is a horizontal cross sectional view

through the heel part of the last showing a still different form of spacing member;

Fig. 10 is a front elevation of the spacing member shown in Fig. 9;

Fig. 11 is a view similar to Fig. 1 showing a different connecting means between the heel and fore parts of the last; and

Fig. 12 is a horizontal cross sectional view through the upper end of a heelpart equipped with a spacing member of the type shown in Figs. 7 and 8.

The construction shown in Fig. 1 comprises a forepart 2 and a heelpart connected to the forepart by a hinge member including a tube 3 which enters a hole bored for it in the forepart and is secured in this hole by a rivet 4. A similar rivet or pivot pin 5 secures the heelpart to the rear end of the tube 3 and allows the heelpart to swing relatively to the forepart. This connection between the two parts of the last is similar to that shown in my Patent No. 1,094,153, granted April 21, 1914, which has proved highly satisfactory in actual use.

The heel portion, as above stated, preferably is made of metal and comprises two side members 6 and 7, respectively, and a central spacing member 8. The side members preferably each consist of hollow metallic shells made, for instance, by punching sheet metal into the required form in suitable dies or they may be made in any other convenient manner. Each of these side members is provided with bottom, side and top faces, and together they constitute the greater part of the shoe supporting surface of the heel portion of the last. The central member 8 is wedge-shaped, as clearly shown in the drawings, with its wide end at the forward face of the heelpart and it tapers backwardly to an edge permitting the rear edges of the side members 6 and 7 to meet at the back of the heelpart and form the shoe supporting surface of this portion of the last.

The adjustment of dimensions of the heel part is effected by removing the central spacing member 8 and substituting for it another spacing member of the size and shape required to cooperate with the side members to produce a heelpart of the necessary dimensions. For the purpose of removably securing the side and central members together a number of different constructions may be used. In the arrangement shown in Figs. 1 to 6, inclusive, the central spacing member 8 is provided with two sets of ears or lugs 9 located at opposite sides thereof, four ears preferably being used on each side, two near the top or cone of the heelpart, and two more near the bottom or anvil surface of said part. The side members 6 and 7 are also provided with cooperating lugs indicated at 10, Fig. 2, one pair of which projects downwardly from the top of each side member, while the other

pair projects upwardly from the bottom of the member. These interengaging lugs 9 and 10 are so arranged that when the central member 8 is pulled forward and the two 5 side members 6 and 7 are pressed against opposite sides of the member 8, the lugs 10 will interlock with the lugs 9, as clearly shown in Figs. 3 and 5. The lugs 9 on the central member are located so close to the 10 top and bottom surfaces of the heelpart that they engage the inner top and bottom surfaces of the side members and thus prevent any relative vertical movement of the three 15 parts of the heelpart. (See Figs. 4 and 6.) It will also be understood from an inspection of Figs. 3 and 5 that the engagement between these two sets of lugs is such that they prevent any relative lateral movement of the three parts of the heel portion. Consequently, the only movement permitted by this 20 construction after the parts have been assembled, as shown in Figs. 3 and 5, is a relative movement longitudinally of the last permitting the central member to move rearwardly relatively to the side members 6 and 25 7. This movement, however, is prevented by the pivot pin 5. It will be seen that each of the side members 6 and 7 is provided with a vertically extending ear or knuckle indicated at 11 and 12, while the central member 30 8 is provided with a similar knuckle 13. Holes are drilled horizontally through these knuckles to receive the pivot pin 5 and when this pin is in its operative position, as shown 35 in Fig. 1, it prevents any relative longitudinal movement of the parts 6, 7 and 8. The three members that constitute the heelpart therefore are secured together so rigidly that they constitute, to all intents and purposes so far as the shoe making operations 40 are concerned, a solid heelpart. The knuckles 11 and 12 turn in sockets formed for them in the end face of the forepart 2 in the same way that the knuckle of a solid 45 heelpart turns in these sockets and the knuckle 13 enters a split or saw-cut formed in the rear end of the tube 3 and thus cooperates with the abutting faces of the fore and heel parts to prevent any twisting or 50 lateral movement of the heelpart relatively to the forepart.

It is obvious that very substantial adjustments in width may be made by this arrangement although the variation indicated 55 in Figs. 3 and 5 probably is fully as great as would be required in actual practice. While the central spacing member 8 usually is wedge-shaped in one direction only, namely, from front to rear, it may also be 60 tapered vertically, if desired, as indicated in Fig. 4 so that the top and bottom of the side members will be held apart by different distances instead of being uniformly spaced apart at any point longitudinally of the 65 heelpart. This construction enables the shoe

manufacturer to secure a very accurate fit between the heelpart and different foreparts merely by using a suitable shaped spacing member 8.

It will be noted that the central spacing 70 member carries the jack spindle socket 14 and the spindle 15 may be made to bottom either in this socket or on the top of the member 8.

A slightly different form of central spacing member is shown in Fig. 7. In this construction the lugs 9 are replaced by angle pieces 15 that are riveted securely to the opposite sides of the spacing member 8' and are spaced slightly from this member at 75 their forward vertical edges in order to receive and lock the lugs 10 on the side members in the same way that the ears 9 cooperate with these parts. The top and bottom edges of these parts 15 bear against the upper and lower inner surfaces of the side members 6 and 7, so that they act as struts or braces to support the side members against pressure exerted on the heelpart in 80 the direction of its height. This pressure in some of the shoe manufacturing processes is very severe indeed, as for instance in the heel operation, and the support thus given to the heelpart is therefore an important practical consideration. 85

Fig. 8 shows a similar construction to that shown in Fig. 7 but in the arrangement of Fig. 8 holes 16 are drilled through the spacing member 8' and the lugs 15 to decrease the weight of the parts. 90

A further modification is illustrated in Figs. 9 and 10 in which the parts 17, corresponding to the struts 15 of the arrangement shown in Figs. 7 and 8, are extended laterally far enough to engage the inner side walls of the members 6 and 7 and thus support the heel against lateral as well as vertical compression. 105

It will be evident that in any of these arrangements the metal is so disposed as to provide a very strong, rigid construction amply capable of withstanding the blows, pressure and rough treatment to which the last is subjected while in use. Furthermore the hollow construction gives this strength and rigidity without excessive weight. 110

Fig. 11 shows the same construction as that illustrated in Fig. 1 except that the knuckle 13' at the forward end of the central spacing member 8 is shaped to cooperate with a ball 18 that is pressed by a spring 19 into engagement with the edge face of the part 13'. A notch 20 is cut in the knuckle 13' in such a manner that it cooperates with the spring pressed ball 18 to hold the last normally in its extended position and yieldingly resists the collapsing movement of the last. This construction is substantially like that illustrated in my prior patent above 120 designated. If desired, however, the last 125

may be held in its extended position by using a spring 21, as shown in Figs. 1 and 2, one end of the spring being secured to the heel part by fitting in a recess and the other end turned at a sharp angle and bearing against the face of the fore part. This spring is tensioned to exert a relative turning movement between the fore and heel parts tending to hold them in their straightened relationship.

It will now be evident that when a shoe manufacturer wishes to change the style of his lasts it is merely necessary for him to substitute a new forepart possessing the required style for the forepart already in use. In order to effect this substitution it is merely necessary to burr off the headed over portion of the pin 4 and drive out this pin. The tube 3 can then be placed in the socket in the new forepart and a rivet driven through and headed over to take the place of the rivet 4. If the new forepart is of the same size as the old one it will rarely be necessary to use a different spacing member, but if this forepart should differ materially in size at its abutting face from the discarded forepart, it is then desirable to remove both pins 4 and 5 and replace the central spacing member 8 with another spacing member of suitable dimensions to widen or narrow the heelpart to fit the new forepart. Such a change when once completed forms a last as rigid and usable in every respect as the ordinary last and one having a heel portion far stronger and more substantial than that of the ordinary wooden last.

This construction is of particular value in those factories in which great attention is paid to standardization of parts and it is of special value at the present time when the difficulty of securing suitable wood for the manufacture of lasts has been greatly increased. While any suitable connection may be used between the fore and heel parts, the form of connection shown is preferred for the reason that it has proved highly satisfactory in actual use and the change from one style of forepart to another involves a very simple operation.

While I have herein shown and described the best embodiments of the invention of which I am at present aware, it is obvious that these embodiments may be variously modified within the skill of the mechanic without departing from the spirit or scope of this invention.

What is claimed as new, is:

1. A heelpart for a last comprising two members forming the opposite sides of said heelpart, and a removable spacing member between said parts serving to hold them in properly spaced relationship, and means for connecting said heelpart to any one of a plurality of foreparts, said connecting means

being operative to secure said parts of the heelpart in their operative positions.

2. A heelpart for a last comprising two members forming the opposite sides of said heelpart, and a spacing member between said side members, said side and spacing members having interlocking parts serving to secure said members together in cooperative relationship and against lateral movement with respect to each other but permitting the removal of said spacing member.

3. A heelpart for a last comprising two members forming the opposite sides of said heelpart, a spacing member between said side members, said side and spacing members having interlocking parts adapted to be interlocked by a relative movement of said members longitudinally of the last and arranged to permit the removal of said spacing member by a relative movement of said members in the reverse direction, and means for securing said members against said relative longitudinal movement.

4. A heelpart for a last comprising two hollow members forming the opposite sides of said heelpart, a spacing member between said side members removably secured to said side members, and interengaging parts on said side and spacing members cooperating to resist pressure exerted on the heelpart in the direction of its height.

5. A heelpart for a last comprising two hollow members forming the opposite sides of said heelpart, a spacing member between said side members removably secured to said side members, and struts carried by said spacing member and cooperating with said side members to resist pressure exerted on the heelpart in the direction of its height.

6. A heelpart for a last comprising two hollow members forming the opposite sides of the heelpart, a wedge-shaped spacing member between said side members locking lugs on said wedge-shaped spacing member, and means concealed within the heelpart and cooperating with said lugs for securing said members in their cooperative relationship.

7. A heelpart for a last comprising two members forming the opposite sides of the last and a wedge-shaped spacing member between said side members and removably secured to them, parts on said side and spacing members cooperating to secure said members together against relative movement in all directions except longitudinally of the last, and means arranged to be rendered operative or inoperative to secure said members against said relative longitudinal movement.

8. A last, comprising a forepart, a heelpart having two members forming the opposite sides of said heelpart and a spacing member between said side members, inter-

locking parts on said side and spacing members cooperating to secure said members together but permitting removal of the spacing member by a relative movement of said members longitudinally of the last, and a pivotal connection removably securing said heelpart to the forepart and also securing said members against said relative movement.

In testimony whereof, I have signed my ¹⁰ name to this specification, in the presence of two subscribing witnesses.
